(57) **CLAIM**

The ornamental design for a combined bracelet and clasp, as shown and described.

DESCRIPTION

FIG. 1 is a front perspective view of a combined bracelet and clasp showing our new design;

FIG. 2 is a back perspective view of FIG. 1;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a perspective view showing the combined bracelet and clasp of FIG. 1 in an alternate state;

FIG. 10 is a perspective view showing the combined bracelet and clasp of FIG. 1 in another alternate state;

FIG. 11 is another perspective view of the combined bracelet and clasp in the alternate state shown in FIG. 10;

FIG. 12 is a perspective view showing areas for enlarged views;

FIG. 13 is an enlarged view of the area indicated in FIG. 12;

FIG. 14 is an enlarged view of the area indicated in FIG. 12;

FIG. 15 is another perspective view showing areas for enlarged views;

FIG. 16 is an enlarged view of the area indicated in FIG. 15;

FIG. 17 is an enlarged view of the area indicated in FIG. 15;

FIG. 18 is another perspective view showing areas for enlarged views;

FIG. 19 is an enlarged view of the area indicated in FIG. 18;

FIG. 20 is an enlarged view of the area indicated in FIG. 18;

FIG. 21 is an enlarged view of the area indicated in FIG. 18;

FIG. 22 is another perspective view showing an area for an enlarged view;

FIG. 23 is an enlarged view of the area indicated in FIG. 22;

FIG. 24 is another perspective view showing areas for enlarged views;

FIG. 25 is an enlarged view of the area indicated in FIG. 24; and,

FIG. 26 is an enlarged view of the area indicated in FIG. 24.

(Continued)

The broken lines in the drawings represent portions of the combined bracelet and clasp that form no part of the claimed design.

FIGS. 1, 2, 5-12, 15, 18, 22 and 24 depict a cursive "L" on the combined bracelet and clasp. A cursive "L" comprises a portion of the mark depicted in the drawing in US trademark application number 88160099, owned by the same entity as the assignee of the present design patent application as recorded in the USPTO at reel 49171 and frame 847. FIGS. 1, 6, 9-13, 15, 18, 22, 24, and 25 depict the letters "LXL" on the combined bracelet and clasp. The letters "LXL" comprise a portion of the mark depicted in the drawing in US trademark application number 88148585, owned by the same entity as the assignee of the present design patent application as recorded in the USPTO at reel 49171 and frame 847.
